John H. Coors

ATTORNEY.

UNITED STATES PATENT OFFICE.

BERRY A. BAXTER, OF MANSFIELD, OHIO.

SWIVEL-BURNER.

No 827,902.

Specification of Letters Patent.

Patented Aug. 7, 1906.

Application filed March 10, 1905. Serial No. 249,368.

To all whom it may concern:

Be it known that I, BERRY A. BAXTER, a citizen of the United States of America, and a resident of Mansfield, in the county of Richland and State of Ohio, have invented certain new and useful Improvements in Swivel-Burners, of which the following is a specification.

My invention relates to a class of burners 10 designated "simmer burners," which are used in conjunction with the ordinary burners in the consumption of gas for fuel or heat.

It is well known to those who are skilled in the art of manufacturing stoves or other 15 heating apparatus that in the construction of the heating apparatus if provision is made for an auxiliary burner it adds greatly to the convenience, utility, and economy in operation. In the construction of the burners 20 now in use the auxiliary or simmer burner is combined with the ordinary burner in a fixed position.

The object of my invention is to construct 25 an auxiliary burner separate and distinct from the ordinary in order to provide facilities for using the burner separate or in combination with one or more ordinary burners.

Another object of my invention is to provide a means of igniting the gas flowing from 30 the ordinary burners by means of the simmer burner.

I attain these and other objects by the mechanism illustrated in the accompanying drawings, in which—

35 Figure 1 is a top plan view of my device in position to be used separate, with dotted lines showing position when used in conjunction with ordinary burners. Fig. 2 is a cross-sectional side view on the line B B of Fig. 4, showing valve, swivel, and burner. Fig. 3 is a side plan view of Fig. 2. Fig. 4 is a top plan view of Fig. 2.

Similar numerals refer to similar parts throughout the several views.

45 In the construction of my device I provide a socket-support 1. An exteriorly-threaded projection 2 is made integral with the support and is fitted to a screw-threaded aperture in the supply-pipe 3. A tapered bolt 4 is fitted to an aperture 5, provided in the socket, leaving the screw-threaded end 6 extending below the lower face of the socket. A needle-valve 7, having a boss 8, with a screw-threaded aperture communicating 55 with the valve-chamber 9, is provided and adapted to engage the screw-threaded end of

the bolt 4, by means of which the valve is supported and swivel movement given to the valve through the medium of the bolt 4. It will be noted that the swivel movement 60 permits of the auxiliary or simmering burner being used separate, as shown in Fig. 1, or in conjunction with one or more burners by turning the valve on the bolt to the position shown by the dotted lines A and B. The 65 valve-stem 10 is provided with a screw-threaded exterior and adapted to fit a screw-threaded aperture 11 in the valve. The end 12 of the valve-stem is tapered, so as to close the orifice 13 or to permit more or less gas to 70 flow through from the chamber. A reducer 14, preferably of the kind shown, having screw-threaded ends adapted to be connected to the valve and the pipe 15. The free end of the pipe 15 is fitted to the inner periphery 75 of the neck of the burner 16. This provides the medium through which the gas flows into the chamber for consumption to the burner. The supply is admitted from the pipe 3 through the orifice 17. An annular groove 80 18 is formed on the bolt 4, intersecting with the inlet-aperture 17. An aperture 19 is provided in the bolt 4 and is adapted to intersect and communicate with the orifice 20, affording facilities for carrying the gas into 85 the chamber of the valve. The burner 16 is preferably made of sheet metal.

Reference-figure 21^a designates the air-inlet. An ordinary packing-nut 21 is used to prevent the escape of gas.

90 It will be noted that the construction of simmer or auxiliary burner, as shown and described, so as to permit the swiveling or turning of the valve and its appliances, greatly increases the efficiency of the heating 95 apparatus and convenience in use.

What I claim, and desire to secure by Letters Patent, is—

1. In a gas burner, comprising a socket, a tapered bolt fitted to an aperture of said socket, said bolt having an annular groove and an orifice provided in the center communicating with a valve-chamber, said orifice and annular groove being connected by an intersecting passage-way, a needle-valve rotatably connected to the threaded portion of the bolt, a reducer connected to said valve, a tube fitted to said reducer on one end, and a burner composed of an upper and lower portion secured to the free end of said tube. 100 105

2. The combination of a swivel-burner, a socket, a bolt fitted to rotate in said socket, a

valve rotatably secured to the threaded end of said bolt, means to conduct the gas from the supply-pipe into said valve, a reducer secured to said valve, a tube connected to said reducer, a burner having an annular chamber, and a contracted central chamber fitted to the free end of the tube as described and set forth.

3. In a burner for gas, a socket having projecting portion adapted to be secured to a supply-pipe a bolt fitted to rotate in said socket, a valve secured to the threaded end of said bolt whereby said valve is rotated, a

reducer secured to one end of said valve, a tube fitted to the end of said reducer, a burner composed of an upper and lower portion having an annular chamber and a contracted central chamber with gas-adjustages provided in the upper portion.

Signed at Mansfield, Ohio, this 13th day of 20
February, 1905.

BERRY A. BAXTER.
